EXCAVATING MECHANISM FOR TRENCH
DIGGING MACHINES

Hermann Klaucke, Worcester, Mass., assignor to
Chain Belt Company, Milwaukee, Wis., a corpora-
tion of Wisconsin

Application June 10, 1947, Serial No. 753,775

5 Claims. (Cl. 37—191)

1

The invention relates to trench digging machines of the kind provided with a digger boom carrying an excavating mechanism of the endless chain type, which machines are now used quite extensively for the digging of relatively narrow but fairly deep trenches in the earth to enable the laying of telephone, telegraph and similar cables below the frost line.

One of the objects of the invention is to provide an improved chain-type excavating unit for such machines, whereby trenches of the character described may be cut more efficiently and expeditiously in practically any kind of earth, including hard stony ground, compact gravel, and firm clay, as well as in lighter and less compact formations.

A further object of the invention is to provide a comparatively light weight single strand chain excavator which may be operated at relatively high speeds, thus increasing the rate at which the trenches may be advanced; and the construction is quite simple, whereby the costs of manufacture and maintenance are materially reduced.

The chain of the excavating mechanism hereinafter described as an illustrative example of a practical embodiment of the invention, is of approximately 3 inch pitch and is of the roller type, with its pin links being of a special construction and each having a hardened toothed cutter member rigidly but readily detachably mounted thereon. This excavator is intended to run at a lineal speed on the order of 1,200 feet per minute, and to cut a trench approximately six inches in width to depths of say from 3 to 5 feet; however these figures are given merely by way of illustration rather than limitation, and all of them may be varied either way without departing from the spirit of the invention.

The excavating unit referred to is shown in the accompanying drawings forming a part of this specification, in which:

Figure 1 is a side elevational view thereof, partly broken away; all portions of the trenching machine itself being omitted except for the sprocket which drives the cutter;

Fig. 2 is a horizontal sectional view on a somewhat larger scale, taken on the plane indicated by the line 2—2 of Fig. 1, looking downward;

Fig. 3 is an enlarged vertical sectional view, partly in elevation, taken approximately on the plane indicated by the line 3—3 of Fig. 1, looking in the direction of the arrows;

Fig. 4 is a side elevational view on a still larger scale, of a pair of adjacent cutter elements, the

2

view being partly broken away and in section, and showing in detail the construction of the chain and the mounting of the cutter members thereon;

5 Fig. 5 is a front elevational view of the parts shown in Fig. 4, as seen from the right thereof; and

Fig. 6 is an end elevational view, as seen from the bottom of Fig. 5.

10 The excavating machine proper (not shown) may be of any well known type having a driving sprocket 10 and a boom or its equivalent to which the plate-like guide member 11 of the present cutter assembly may be vertically adjustably attached by means of one or more bolts passing through the elongated slot 12. At its lower end the opposed faces of the guide member are rabbeted as at 13 to receive the upper end portions of plates 14 which are secured to the member 11 by bolts 15, and the lower portions of which mount an antifriction bearing 16 which journals a lower or foot sprocket 17.

An endless chain 18 is trained about the sprockets 10 and 17, said chain being of the roller type comprising alternating roller links 19 and pin links 20, connected by headed or riveted chain pins 21. As best shown in Fig. 4, the roller links 19 are of a more or less conventional construction, comprising spaced side bars 22 rigidly connected by tubular bushings 23 upon each of which is journaled a roller 24. The bores 25 of the said bushings journal the intermediate portions of the chain pins 21.

25 As above indicated, the pin links 20 of the chain are of a special construction and comprise U-shaped stampings the legs 26 of which constitute the link side bars which are provided adjacent their ends with apertures 27 for receiving the end portions of the chain pins 21. These pins are held against rotation in such apertures by complementary flats 28 formed on the pins and the aperture walls, and thus wear which inevitably occurs in the articulating joints of the chain is caused to take place in the roller links, 40 which are less expensive to replace than the pin links.

The bridge or cross member 20 of the pin links 20 have plates 31 rigidly secured to their outer faces, as by welding at 32. The plates 31 are of a width slightly less than that of the trench to be cut, while their length is such that in the straight runs of the chain between the sprockets the adjacent plates provide a substantially continuous wall disposed outwardly of the chain 45 and tending to protect it from the excavated

matter. A bracket 34, comprising a base plate 35 having an angular extension 36, and side wings 37, is removably secured against the forward face 33 of each plate member 31, as by bolts 38 passing through the bridge member 30, plate 31 and bracket base 35, as will be clear from Figs. 4, 5 and 6.

The extension 36 of the bracket is disposed at an angle of approximately 45° to the face 33 of the plate 31, and a cutter member 40 is removably secured to such extension, as by bolts 41. The said cutter member comprises a quadrangular plate of hardened steel or the like, the base of which is of a width substantially equal to that of the plate 31 and is beveled as at 42 to fit tightly against the face 33 of such plate. The sides of the cutter plate flare laterally outward from said base, as indicated at 43, to the forward or cutting end of the member, which is provided with a plurality of transversely spaced teeth or picks 44 of triangular cross section.

As will be clear from Fig. 5, alternate cutters 40 are provided respectively with an odd number and an even number of teeth or picks 44, with those of one member being transversely staggered relative to those of the adjacent member, thereby traversing different longitudinal paths. The teeth may thus be made rugged enough to withstand repeated contact with stones or the like, while at the same time the teeth of any pair of adjacent cutters will act to dislodge material throughout the width of the cut. The teeth are given a forward clearance angle of approximately 15°, as indicated at 45 (Fig. 4); and their entire formation is such that they are self-sharpening in use.

As best seen in Figs. 1 and 2, the vertical edges of the guide member 11 are rabbeted as at 50, providing a tongue 51 which extends between the side bars of the chain links 19 and 20 for engagement by the chain rollers 24. The guide member thus not only backs up the chain and cutters to maintain the cutting run between the sprockets perfectly straight, but it also prevents lateral shifting of these elements in the cut.

As each cutter 40 reaches the bottom of the foot sprocket 17 its teeth 44 engage the ground in much the manner of picks, loosening the earth and gravel and, due to the high velocity, breaking up lumps and stones of reasonable size. This action continues through the balance of the arcuate sweep of the cutters and through their upward travel to the ground surface, the disintegrated material sliding back on the now inclined body of the cutter plate 40 into the pockets formed by adjacent cutters, the plates 31 and the cutter supporting brackets 34. As the cutters reach the ground level most of the material will be discharged from the sides of the pockets, to either side of the trench, although because of the high speed, some of it may be carried up to the head sprocket 10, where it will be thrown out by centrifugal force as the cutters pass around such sprocket. The sprocket of course should be hooded or otherwise shielded to prevent injury to workmen or damage to other parts of the apparatus.

With each pin link of the chain provided with a cutting member 40, in the illustrative example cited above of a 3 inch pitch chain, the distance between adjacent cutters will be six inches. If such an excavating unit be driven at say 1,200 feet per minute there will thus be 2,400 cuts per minute, and if the trenching machine be advanced over the ground at a rate of 30 feet per

minute (approximately 2.75 miles per 8 hour day) the bite for each cutter will be only 0.15 inch. These relatively light cuts reduce strain and wear and tear on the apparatus, and permit the construction of the chain and cutters to be appreciably lighter than heretofore, which in turn is conducive of the higher chain speed.

Although the excavating unit has been illustrated in the drawings as operating in a vertical position, it will function in the same manner and just as efficiently if inclined to the vertical, as is sometimes done in the art.

What is claimed is:

1. A high speed excavating mechanism for narrow-trench digging machines, which machines are provided with a horizontally mounted driving sprocket and with means for supporting the excavating mechanism in operative position below such sprocket: said mechanism comprising an elongated upright guide plate attachable to said supporting means in alignment with said sprocket; a single endless strand of chain comprising a series of pintle connected links engageable with said sprocket, said chain having an ascending run traversable along and in engagement with the forward edge of the guide plate whereby the latter may support the chain against deflection in such run; a protecting plate carried by each alternate link of the chain outwardly thereof and extending laterally beyond each side of the chain to substantially the full width of the cut, said protecting plates being of a length to overlap the connecting links, whereby they may abut one another in said ascending chain run and provide a continuous protecting wall outwardly of the chain; and a plate-like excavating and conveying member secured to and extending forwardly at an acute angle from each of said alternate links, each such member being of a width equal to that of the trench to be cut, and overlapping the protecting plate of the preceding link to form therewith a material receiving and conveying pocket.

2. An excavating unit for trenching machines, comprising a single endless strand of sprocket chain composed of pivotally connected links, alternate ones of which are of U-shaped cross section; a plate member secured to the outer face of the cross member of each of said U-shaped links and extending laterally to each side thereof to substantially the full width of the cut to be made, the ends of adjacent plates substantially abutting one another in the straight cutting run of the chain to provide a wall forwardly of the latter which protects it to the full width of the cut against entry of excavated material into and around its links; and a flat cutter member secured to each of the U-shaped links and extending angularly forward from the plate thereof, and provided along its forward edge with a plurality of transversely spaced pick-like teeth.

3. A narrow-trench excavating unit for trenching machines, comprising a single endless strand of sprocket chain composed of pivotally connected links, alternate ones of which are of U-shaped cross section; a plate member rigidly secured to the outer face of the cross member of each of said U-shaped links and extending laterally to either side thereof, said plates being of a length to substantially abut one another when the links are aligned in the straight cutting run of the chain; a bracket member detachably secured to each U-shaped link outwardly of its plate and having an extension projecting forwardly from the latter at an acute angle thereto; and a flat

cutter member detachably secured to and paralleling said angular extension of each of said brackets, the forward edge of each cutter member being provided with a plurality of transversely spaced pick-like teeth.

4. A cutter element for a narrow-trench excavating unit of a trenching machine, comprising a sprocket chain link of U-shaped cross section; a plate member secured to the outer face of the cross member of said link, and extending laterally to either side thereof; a bracket detachably secured to said link cross member and plate, said bracket having an extension projecting forwardly from the outer face of the plate member at an acute angle thereto; and a flat cutter member detachably secured to and paralleling said bracket extension, the forward edge of said cutter member being provided with a plurality of transversely spaced pick-like teeth.

5. A cutter element for a chain type excavating unit of a trenching machine, comprising a sprocket chain link of U-shaped cross section providing spaced side bars connected by a cross member, said side bars having pin-receiving apertures adjacent their ends; a plate member rigidly secured to the outer face of said cross member and extending laterally to either side thereof, said plate member being of a length substantially equal to that of the link; a bracket having a base detachably secured to said link cross member, and an extension projecting forwardly from

the outer face of said plate at an angle of substantially 45°, said bracket also having side wings connecting said base and extension; and a quadrangular plate-like cutter member detachably secured to and paralleling said bracket extension and having a bevelled heel abutting the face of said link plate member, the forward edge of said cutter member being provided with a plurality of transversely spaced digging teeth of triangular cross section.
